UNITED STATES PATENT OFFICE.

WILLIAM S. MCRAY, OF COSMOPOLIS, WASHINGTON.

DESIGN FOR A DISPLAY-RACK.

SPECIFICATION forming part of Design No. 33,761, dated December 18, 1900.

Application filed November 13, 1900. Serial No. 36,410. Term of patent 3½ years

To all whom it may concern:

Be it known that I, WILLIAM S. MCRAY, a citizen of the United States, residing at Cosmopolis, in the county of Chehalis and State of Washington, have invented and produced a new and original Design for Display-Racks, of which the following is a specification.

As shown in the drawing, my design for a display-rack consists of a rectangular top piece or shelf A, from the longitudinal edges of which depend legs or supports B at substantially the inclination shown, there being four legs on each of the longitudinal edges of the top piece. Each pair of the legs or supports when viewed from the side extend parallel one with the other and when viewed from the end diverge. Between each set of legs are positioned rectangular pieces C, which pieces increase in size from the top shelf A downward, and the legs or supports extend a short distance below the lower and larger rectangular cross-piece, and the upper ends of the supports terminate on a line with the upper surface of the top piece A. A cross-piece D extends from one of the shelves C to a shelf on the opposite side.

One of the material features of this design resides in the supports which are made up of side members positioned to be parallel when viewed from the side, said members diverging or widening out from the top to the bottom when viewed from the end, said features together with the rectangular pieces or shelves which are between the supports, said shelves increasing in length from the top downward, and, as shown, similar supports and shelves are secured on each side of the center of the top piece.

Having thus described my invention, what I claim, and desire to secure by Letters Patent, is—

The design for a display-rack, as herein shown and described.

In testimony whereof I have hereunto set my hand in presence of two subscribing witnesses.

WILLIAM S. MCRAY.
